MEANS OF COMPENSATING FOR DRIFT OF PHOTOELECTRIC DEVICES AND ASSOCI- ATED CIRCUITS

Konstantin Woloschak, Port Chester, N. Y., as-
signor to Press Association, Inc., New York,
N. Y., a corporation of New York

Application September 17, 1942, Serial No. 458,642

14 Claims. (Cl. 178—6.7)

This invention relates to means for compensating for the gradual drift of the signal output voltage of an electron amplifier or a photoelectric cell, and the gradual change in the overall gain of transmission circuits. In accordance with some applications of this invention compensation for the drift of either transmission circuits, the photoelectric device or its associated circuits, or the two in combination, may be accomplished.

A specific object of this invention is the application thereof for use with facsimile picture transmission systems.

The detailed objects of the invention and details of various circuit arrangements for accomplishing those objects are set forth below in connection with the attached drawings in which the same or similar reference numerals are used throughout to indicate the same or similar parts.

This invention resides substantially in the combination, construction, arrangement, relative location of parts, steps and series of steps, all as will be explained in full detail hereinafter.

In the accompanying drawings.

Figure 1 is a diagrammatic and circuit schematic arrangement illustrating one embodiment of the invention as applied to the transmitting equipment of a facsimile picture transmission system.

Figure 2 is a left hand end elevational view of the rotatable cylindrical support for the picture to be transmitted.

Figure 3 is a schematic circuit arrangement showing a modification which may be applied to the circuit arrangement of Figure 1.

Figure 4 is a diagrammatic view of a modified form of the portion of the apparatus of Figure 1 involving the picture support and scanning head.

Figure 5 is a left hand end elevational view of the rotatable picture support of the structure of Figure 4.

Figure 6 is a view similar to Figure 4 of a further modified construction.

Figure 7 is a complete diagrammatic and circuit schematic arrangement involving a still further modified form of transmission equipment of this type embodying the invention with further modifications.

Figure 8 is a diagrammatic illustration of the application of this invention in the correction of gradual variations in a transmission line or other communication channel.

Figure 9 is a diagrammatic illustration of the application of the subject matter of this invention to a system wherein the gradual drift in the signal output voltage of a photoelectric device and the gradual variations in the connected transmission line or other communication channel are compensated for.

In the use of photoelectric cells and electron

multipliers of the photoelectric type, as for example when used in connection with facsimile picture transmission systems, there is inherent therein, as well as in the circuits associated therewith, a tendency for the signal voltage to change gradually due to the drifting of the output voltage of the photoelectric devices and to a gradual over-all change or drift in the gain of the circuits associated therewith. It is the prime object of this invention to provide means for automatically compensating for either of these drift components, or for both of them.

In accordance with this invention the voltage drift of the photoelectric devices and associated equipment at the transmitting station may be compensated for by association of the herein disclosed invention with the equipment at the transmitter. Similar results can be secured by the appropriate application of this invention to the transmitter and receiver to accomplish correction of the gradual variations in the transmission line or other communication channel therebetween. As a final application of this invention, portions thereof may be associated with the transmitting and receiving equipment to compensate both for the drift of the photoelectric devices and for the associated and interconnecting circuits. These various applications of the invention will be separately described hereinafter.

Referring to Figure 1 of the drawings, a rotatable cylinder 1 of the type usually employed in facsimile picture transmission is diagrammatically illustrated to include a shaft 2 for supporting it for rotation on its longitudinal central axis.

The picture such as a photograph to be transmitted, is diagrammatically illustrated at 2 applied around the periphery of the cylinder 1 and attached thereto at its top and bottom edges by means of a wedge bar 4 which clamps the top and bottom edges of the photograph into a longitudinal slot in the cylinder 1 and holds the photograph in intimate contact with the cylinder 1 throughout its area. Clamping bars of this type are commonly used in such systems. As a part of this invention a special contact 5 is mounted on the end of the cylinder 1 and aligned with the end of the clamping bar 4 in a radial direction for cooperation with contacts which will be referred to later.

Only so much of the scanning head has been diagrammatically illustrated herein as is necessary to an understanding of the invention. The parts illustrated are enclosed within a dash line box for the purpose of indicating that the scanning head 6 is a structural unit which, as is well known in this art, is driven in synchronism with the rotation of the cylinder 1, so that it slowly moves longitudinally thereof. As illustrated, this unit includes a light source 7 the light from which

is focused by a lens system 8 to a point P on the surface of the photograph 2 along an axis at an angle so that the light reflected from the point P is refocused by a lens system 9 onto the pickup photoelectric cell 10 or electron multiplier having a photoelectric cathode.

With this arrangement, as is well known, when the transmitter is in operation the point P has a helical path of relative travel with respect to the photograph 2, so that the point gradually traverses the entire surface of the photograph 2 and thereby scans each elemental area thereof. The output of the photoelectric device 10 varies in accordance with the reflective characteristics of the elemental areas scanned. The output of the photoelectric device 10 has been diagrammatically illustrated as being supplied by means of the circuit wires 11 to an amplifier 12, preferably of the vacuum tube type, and associated equipment. Circuits of this type are well known in the prior art and one form of this circuit is illustrated in the co-pending application of James C. Barnes, Serial No. 428,813, filed January 15, 1942.

The amplified signal currents are supplied from the amplifier 12 by circuit wires 13 and 14 to the primary of the input transformer 15 of the multi-stage vacuum tube signal amplifier, as illustrated.

The secondary of transformer 15 is connected in the input circuit of a triode vacuum amplifier 16 whose output circuit is connected by the coupling transformer 17 to the input circuit of a second triode vacuum tube amplifier 18. As a further aid in the application of this invention it may be noted that these triodes may be the commercially known 7H7 tubes connected so as to be used as triodes. The output circuit of this amplifier is connected by the coupling transformer 19 to the transmission line. Anode voltage supply is connected to the lead 20 in accordance with well known practice.

In accordance with this invention, the compensating device is associated with this amplifier in the following manner. The output leads 13 of the amplifier 12 are also connected to the primary of a coupling transformer 20 whose secondary is connected in the input circuit of a diode vacuum tube detector 22. This input circuit includes a pair of contacts 22 arranged to be interconnected by means of the contact 5 mounted on the cylinder 1. Contacts 22 are connected by the wires 21 in the input circuit of the diode. The output circuit of the diode includes a network 24 comprising a condenser C and a resistor R. This network 24 has a relatively high time constant due to the fact that the capacitance and the resistance of which it is composed are large. Common lead 20 extends from the network 24 to the cathodes of the triodes 16 and 18. An adjustable connection 25 from the resistor R is connected to the input circuits of the triodes 16 and 18 through the resistors 26 and 27. By-pass condensers are connected between the points of connection of the cathodes of the triodes 16 and 18 to the lead 20 and the points of connection of the resistors 26 and 27 to the input circuits of those triodes.

In the operation of this system it will be seen that the input circuit to the diode 22 will be completed once for each revolution of the cylinder 1, that is, at the time the contacts 22 are interconnected by the contact 5. At this time the light point P will be projected upon the surface of the clamping bar 4. This clamping bar should be made to have uniform reflective characteristics

and should preferably be white although a gray or other tonal value would be suitable. It thus provides a reflection standard of uniform reflecting power throughout its length so that the light reaching the photoelectric device 10 provides a standard reference signal. Since the contact 5 and strip 4 are radially aligned, the signal voltage output of the electron device 10 is a maximum once for each revolution of the cylinder 1 at the time that the input circuit for the diode is complete at the contact 5.

At this time the voltage developed across the resistor R is determined solely by the signal voltage generated by the light reflected from the strip 4. If the output signal voltage of the photoelectric device 10 drifts or changes gradually, due to the drifting of the operating voltage of the electron device, or to a gradual change in the over-all circuits connected between it and the detector 22, the voltage across the resistor R will likewise change slowly. This rectified voltage across the resistor R can be used as illustrated in Figure 1 to vary the grid bias voltage of one or more of the triodes of the amplifier (in the case illustrated this bias control is shown for both stages of the amplifier) to compensate for the original signal voltage change resulting from the drift components mentioned. The average value of this compensating voltage can be controlled by adjustment of the connection of line 25 to the resistor R as illustrated.

In order to increase the sensitivity of this arrangement, the modification of Figure 3 may be employed, which consists solely of inserting in the connection between the resistor R and the lead 20 a battery or other source of constant voltage 30 so that it is in opposition in polarity to the compensating bias voltage generated in the resistor R.

The voltage value of the source 30 should be almost equal to the compensating bias voltage drop in the resistor R. From an examination of Figure 3 it will be obvious by reason of the use of the same reference numerals how to apply the feature of Figure 3 to the circuit of Figure 1. By this use of the biasing voltage source 30 it will be apparent to those skilled in the art that the effect of the voltage variations across the network R will be more directly proportional to the variations in the energy input from the circuit 13 than in the case of the arrangement of Figure 1 where the source 30 is not employed. The reasons for this are at once apparent to those skilled in circuit operations.

The arrangement of Figures 4 and 5 contains a variation of a portion of the invention heretofore disclosed wherein the use of the clamping bar 4 is dispensed with as a source of maximum reflection and a special white target, moving in timed relation with the cylinder, is employed. In this case the light from the source 7 is focused upon a white target 38 which is connected to a shaft on which is mounted a bevel gear 31 for rotation therewith. The bevel gear 31 in turn meshes with a bevel gear 32 which is splined to the shaft 33 so that it may progress therewith as it revolves with the shaft. The target and gears are mounted on and form a part of the scanning head 8 so that they may move with the other parts of the scanning head longitudinally of the cylinder 1 in accordance with common practice. Shaft 33 is provided with a gear 34 which meshes with a gear 35 mounted upon the shaft 3 for rotation with it and the cylinder. These various parts are proportioned so that as the power driv-

en cylinder 1 operates, the target 30 will be interposed between the light source and photocell and the cylinder 1 once for each revolution of the cylinder during the scanning of the clamping bar for the photograph mounted thereon.

Also mounted on the shaft which supports the cylinder 1 is a cam 5' which functionally is a substitute for the contact 5 of Figure 1. This cam cooperates with a pair of spring fingers 22' and is shaped so that once for each revolution of the cylinder 1 these spring fingers engage and complete the circuit of the wires 21 to which they would be connected in a system such as that of Figure 1. Cam 5' is, of course, positioned properly so that at the time the target 30 intercepts the light circuit source 1 spring fingers 22' will engage. It is at once apparent how this modification may be applied to the circuit of Figure 1.

One advantage of this arrangement is found in the fact that the white target 30 will each time present the same reflecting conditions, whereas in the arrangement of Figure 1 where the clamping bar is employed there may be some variations in reflective qualities along the length of the bar due, for example, to the collection of dirt during use. Likewise the white target 30 will only change in color but slowly as it becomes dirty, so that any variations in the automatic control which would therefore result will occur but slowly over long periods of time.

A further modification is shown in Figure 6 wherein the clamping bar 4' is in this case definitely made non-reflecting. In this arrangement the shaft 33 is provided, as in the previous arrangement, and geared by means of the gears 34 and 35 to the shaft 3. The cam 5' and spring fingers 22' are used as before. In this arrangement, however, a disc 36 is splined on the shaft 33 and moves with the scanning head 6 as it revolves. This disc is provided with an aperture 37. A separate light source 38 is provided and positioned so that the aperture 37 will be aligned therewith with the result that the photoelectric device 10 is brightly illuminated from the source 38 once for each revolution of the cylinder 1.

The opening 37 is positioned on the disc 36 so that it is aligned with the light source 38 at the time that the light source 1 is striking the non-reflecting clamping bar 4'. The parts are so proportioned of course that the opening 37 of the shutter becomes aligned with the light source 38 once for each revolution of the cylinder 1. The arrangement of Figure 6 may be readily introduced into the full combination of Figure 1 in an obvious manner, and the proper adjustments can be effected either by controlling the intensity of the light of the source 38 or by varying the size of the opening 37 in the shutter 36 to provide the proper compensating voltage. A similar effect could be secured by eliminating the shutter 36 and substituting a neon lamp for the light source 38, in conjunction with a proper timing device to energize the neon light once for each revolution of the cylinder 1 and at the time the scanning bar 4' is being scanned. In this arrangement the intensity of the light from the neon lamp would, as before, be adjustable to give the proper effect by varying the voltage applied to the neon lamp in any well known manner. It is, of course, apparent that an additional pair of contacts could be provided to be operated by the cam 5' to complete the neon light circuit at the correct time.

Another system in accordance with this inven-

tion is shown in full detail in Figure 7. As illustrated, the scanning head in this instance employs the structure illustrated in Figure 4. The output of the photoelectric device 10 is passed through the amplifier 12, as in the case of Figure 1, and supplied to the circuit wires 13 and 14 as before. The main difference in this arrangement over that of Figure 1 is the provision of an additional network having a large time constant associated with the network 24 to maintain the compensation bias voltage more nearly constant during each revolution of the cylinder.

In the arrangement of the circuit of Figure 1, no matter how large the time constant of the network 24 (and practical considerations will not allow it to be more than a few seconds) the rectified voltage developed across the resistor R gradually decays during the period of rotation of the cylinder when the contacts 22 are open. Under this obvious condition, while valuable compensation is secured, the compensating bias voltage does vary in a definite repetitive fashion during each revolution of the cylinder. This variation may be large enough to produce noticeable effects on the received negatives. The arrangement of Figure 7 overcomes this difficulty and renders the application of this invention more perfect. This improved result is accomplished by employing an additional network 100 comprising the capacitor C' and the resistor R' across which a bucking voltage of a value almost equal to but opposite in polarity to that developed across the network 24.

The time constant of the network 100 is adjusted so as to be equal to or slightly less than that of the network 24. The voltage across the resistor R' varies with time in a manner similar to the variation of the voltage across resistor R, and the resulting difference between the two voltages is a substantially constant bias voltage which is fed to the input circuits of the triodes 16 and 18 just as in the case of the circuit of Figure 1. Since the voltage across resistor R is always somewhat larger than that across resistor R', the time constant of the network 24 should be a little larger than that of the network 100 to maintain more nearly a constant voltage difference between them, i. e. biasing voltage, while the contacts 22 are open. In order to provide the necessary bucking voltage for the network 100 the plate supply circuit for the triodes 16 and 18 is tapped by the insertion of a resistor 60 therein which is connected by adjustable tap lead 61 through the contact fingers 22'' and wire 62 back to the network, as shown, so that a desired portion of the resistor 60 may be connected across this network by the connections 62 and 70.

In this arrangement the cam 5' not only opens and closes the contacts 22, but also the contacts 22'' at the instant that the target 30 intercepts the light from source 1 which is at the time the bar 4 would otherwise be scanned. It will at once be apparent to those skilled in the art that this bucking voltage could be supplied by a separate battery in the lead 61, which in this case would connect directly to the wire 70 instead of being supplied by tapping the plate circuit as described. With this system the bias voltage remains more nearly constant during each rotation of cylinder 1.

There has been diagrammatically illustrated in Figure 8 the application of this invention to a facsimile picture transmission system for compensating for the gradual variations in the transmission line or other communication channel in-

terconnecting the transmitter and receiver of such a system. This is a good point to note, that the application of this invention to facsimile picture transmission systems does not represent the only use to which the subject matter of the invention may be put. Particularly it is to be noted in connection with the application of the invention as illustrated by Figure 8, that the subject matter of this invention may be used for improving transmission line characteristics generally. Only sufficient of the transmitter and receiver of a facsimile picture system is illustrated in Figure 8 to make the subject matter of the invention clear. The transmitting cylinder or support 1, rotatably mounted on the shaft 3 and provided with the cam 5', is like that previously described in connection, for example, with the description of Figure 1. In this arrangement, however, the receiving support for the receiving negative is illustrated as likewise comprising a rotatable support 40 provided with a shaft upon which a cam 41 similar to the cam 5' is mounted. The scanning and recording heads have not been shown as unnecessary to an understanding of the invention. The signal to be transmitted, such as the picture signal, is fed by the circuit 13 into the transformer 42 and may come directly from the scanning head or an amplifier fed by the scanning head. The cam 5' operates a single pole double throw switch 43 whose movable blade is operated by the cam. One of the fixed contacts thereof is connected to one terminal of the secondary of transformer 42. The other terminal of this secondary is connected to one terminal of the secondary of a transformer 45 and to one of the transmission circuit lines 46. The movable contact of switch 43 is connected to the other transmission circuit line 46. The other terminal of the secondary of transformer 45 is connected to the other fixed contact of switch 43. The primary of the transformer 45 is fed by a suitable signal source 44, preferably an alternating current generator of constant amplitude. The broken line box 41 represents the transmission line or communication channel between the transmitter and the receiver with its usual adjuncts and in the various known suitable forms.

The incoming signal from the transmission line is fed to a transformer 42 whose secondary is connected at one terminal to the movable contact of a switch 43 operated by the cam 41 on the receiver. The fixed contact of this switch is connected to the cathode of a diode rectifier 57. The plate circuit of the diode is connected to the other terminal of the secondary of transformer 42 through a network 51 comprising a potentiometer shunted by a capacitor. Shunted across the incoming end of the transmission line is a transformer 52 whose secondary is connected to the input of a triode 55 forming part of the compensating amplifier indicated by the broken line box. This input circuit includes the bypass condenser 53. The output circuit of the triode 55 feeds a transformer 56 whose secondary is connected in a known manner, not shown, to the recording head of the receiver of which the cylinder 40 is a part. The signal current in this secondary circuit represents the compensated signal from the transmitter, that is, the signal from the transmitter compensates for any variations introduced by changes in the transmission efficiency of the channel 41. This compensation is effected by reason of the connections from the network 51 across the terminals of the

condenser 53 in the input of the triode 55. The resistor 54 is provided for the obvious purpose of creating the proper circuit conditions in conjunction with the adjustment of the potentiometer of the network 51.

It will be seen that the compensating amplifier and its manner of connection with the diode rectifier and other portions of the circuit is similar to that previously described and only 10 differs in that the compensating amplifier is shown as having one stage, it being understood, of course, that the required number of stages may be employed as previously indicated in connection with Figure 1. It is, of course, apparent 15 that the operation of this system depends upon suitable synchronism, the requirement for which is indicated by the relative positions of the cams 5' and 41. In other words, when the reference signal source 44 is in circuit at switch 43, switch 20 43 must be closed so that the compensating signal circuit is in operation.

In the actual application of this invention these conditions will preferably exist at the 25 interval between scanning strokes. For example in the case of the rotatable support type of facsimile system, these conditions would be maintained at the time the scanning head and recording heads are aligned with the clamping bars of the supports. In the case of the reciprocating type of supports, this condition would exist 30 during the return stroke of the supports at which time scanning and recording does not take place. To summarize, the receiving end of the line is periodically connected to the rectifier 35 circuit for controlling the gain of the amplifier at the time the reference signal source is connected in circuit, all of which should occur at the interval between what may be termed the scanning strokes. This application of the invention will be seen to differ from those previously 40 described in that the reference signal is, in the former case, produced by a separate reference signal generator 44 as distinguished from the case of the latter where this signal is gotten by the use of a target in one form or another of uniform reflection characteristics.

The arrangement of Figure 9 will be described, wherein is illustrated the application of this invention to a facsimile picture transmission system 55 in order to compensate not only for a drift 60 in the signal output voltage of the electronic device, but also for variations in the transmission efficiency of the channel connecting the transmitter to the receiver.

In the system illustrated diagrammatically in Figure 9, both the transmitter and receiver have 65 been shown. As illustrated, the transmitter includes a suitable support such as a drum 1, mounted upon the shaft 3 so as to be rotatable in use. The positive or other form of scene 2 to be transmitted is mounted on the drum 1 and is held thereon by means of the clamping bar 4. At the receiver a similar support 40 is rotatably supported on the shaft 41 and has attached 70 thereto the sensitized recording negative 2', by means of a clamping bar 4a. In the application of this invention, as in the usual case of the operation of such a system, the rotation of the drums 1 and 40 will be accurately synchronized.

The scanning head unit 6 includes, as before, a constant source of light 7 of suitable form and a focusing lens system 8 for focusing the light from the source onto the photograph 2 in the form of an intense but extremely small spot of light. Suitably positioned to receive the light

reflected from the photograph is a focusing lens system 9 arranged to focus the reflected light on a suitable photoelectric device 10. The scanning head unit 6 of course moves in timed relation with the support 1 so as to slowly travel in an axial direction from one end to the other during scanning.

At this point it may be noted, as those skilled in the art will appreciate, that the subject matter of this invention in all of its various forms, may be equally well applied to a facsimile picture transmission system where the scene to be transmitted is in the form of a transparency and the scanning head of a type employing transmitted rather than reflected light.

As in the case of the system of Figure 4, for example, a rotatably supported target 30 of uniform reflecting characteristics is caused to rotate by means of a pair of meshing bevel gears 31 and 32. The bevel gear 32 is splined to the shaft 33 on the end of which is a gear 34 meshing with a gear 36 secured to the shaft 3. Similarly the parts are proportioned so that the target 30 makes one complete revolution for each revolution of the drum 1 and hence is interposed between the light source 7 and photoelectric cell 10 once for each rotation thereof.

The output of the photoelectric cell is applied by the circuit wires 11 to the input of a transmission amplifier 12 whose output terminals are connected to the transmission line channel or network 47 connecting the transmitting station with the receiving station. In this system the signal voltage is amplified and compensation is applied to the amplifier at the receiving station. The channel 47 is coupled to the signal amplifier by means of a transformer 15 which corresponds to the similarly numbered transformer at the transmitter in the system of Figure 1. A multi-stage signal amplifier is employed, as before, including the triode amplifiers 16 and 18. The compensating detector in the form of a diode 23 has its input circuit coupled to the receiving station terminals of the channel 47 by means of the leads 13 and the transformer 20. In this case the input circuit of the diode 23 is connected by the leads 21 through a switch 22a which is operated by means of a cam 41 on the shaft 41' so that the switch 22a closes once for each revolution of the support 40. The compensating detector circuit and its manner of connection to the received signal amplifier is the same as that of the arrangement of Figure 1. In this case, however, the anode circuit of the triode 18 includes the signal operated recording lamp 208 in the recording head of the receiver.

In the operation of this system, once for each revolution of the transmitter the target 30 is interposed to cause excitation of the photoelectric device 10 at a uniform value to provide a reference signal which is amplified, sent over the transmission line, and applied to the compensating detector 23. As before, the output of this detector is applied to the received signal amplifier to bias it to a value which will compensate in this arrangement not only for any drift or variation in the signal output voltage of the photoelectric device 10, but for any variation or change in the transmission line characteristics. As illustrated, this reference or compensating signal is preferably applied at the time the scanning head and the transmitter would be scanning the clamping bar 4, which is also the time when the light from the recording lamp 208 is impinged upon the clamping bar 4a of the

receiver. Thus the visible light variation due to the compensating signal will not affect the sensitized negative 2'.

For the purpose of orienting the reader's viewpoint, it may be noticed that the systems of Figures 2 and 9 are quite similar in the equipment used, and they really only differ in two main respects. Firstly, the switch 22 of the system of Figure 1 which has been designated switch 22a of the system of Figure 9, has been moved from the transmitter to the receiver. Secondly, the compensating detector has likewise been shifted from the transmitting end to the receiving end of the line. The received signal amplifier is equivalent to the amplifier at the transmitting end of the system of Figure 1 but in actual use may not really be the same amplifier because it is common to employ a signal amplifier at the receiving station so that in applying the system of Figure 9 the biasing detector 23 and its associated circuits are simply applied to the receiving amplifier.

It will be apparent from the above description that the subject matter of this invention can be widely varied as suggested by the modifications herein disclosed, and I do not, therefore, desire to be strictly limited to the disclosure as given for purposes of illustration, but rather to the scope of the appended claims.

What is claimed is:

1. The combination with a facsimile picture transmitter having a scanning head including a photoelectric device, and an amplifier fed by said device, of means operated periodically by said transmitter for applying a bias voltage to said amplifier to correct for the signal drift of said photoelectric device.
2. The combination with a facsimile picture transmitter having a scanning head and a transmission circuit connected to said scanning head, of means operated periodically by said transmitter for applying a compensating voltage to said transmission circuit at the transmitting end to compensate for inherent signal drift therein.
3. In a system of the type described the combination including a facsimile picture transmitter composed of a rotatable support for a picture to be transmitted, a scanning head including a light source and a photoelectric device, means for causing timed relative movement between said support and scanning head, a transmission network connected to said photoelectric device, and means operated in timed relation with said support to apply a compensating voltage to said network at its transmitting end once for each rotation of said support.
4. In an apparatus of the type described, the combination comprising a movable support for a picture to be transmitted, a reflecting member moving in timed relation with said support, a scanning head including a light source and a photoelectric cell, means for causing a desired relative movement between said support and scanning head, a transmission circuit connected to said photoelectric cell, and means controlled by said relative movement for applying a biasing voltage to said network at its transmitting end to compensate for inherent signal drift in said network.
5. In an apparatus of the type described, the combination comprising a movable support for a picture to be transmitted, a reflecting member, a scanning head including a light source and a photoelectric cell, means for causing a desired relative movement between said support, scan-

ning head and reflecting member, a transmission circuit connected to said photoelectric cell, and means controlled by said relative movement for applying a biasing voltage to said network to compensate for inherent signal drift in said network and in said photoelectric cell.

6. In a transmitting apparatus of the type described, the combination comprising a movable support for a picture to be transmitted, a reflecting member driven in timed relation with said support, a scanning head including a light source and a photoelectric cell, means for causing a desired relative movement between said support and scanning head, a transmission circuit connected to said photoelectric cell, and vacuum tube repeating means including a network having a predetermined time constant operated as a result of said relative movement each time said reflecting member is exposed to said light source to apply a compensating voltage to the network at the transmitting end to compensate for inherent signal drift therein.

7. In a transmitting apparatus of the type described, the combination comprising a facsimile picture transmitter having a rotatable support for a picture to be transmitted, a reflective member synchronized with said support, a scanning head having a light source and a photoelectric device, means for causing relative longitudinal movement between said support and scanning head as the support rotates, a transmission network connected to said photoelectric device, and means connected to said transmission circuit and operated each time said reflective member is scanned by said light source to apply a compensating biasing voltage to the network at its transmitting end.

8. In a facsimile picture transmission system, the combination including a rotatable support for a picture to be transmitted, a scanning head including a light source, a photoelectric cell, and a movable reflective target, means for causing relative longitudinal movement between said scanning head and support as the support rotates, and for causing said target to move between said light source and support once for each rotation thereof, a transmission network connected to said photoelectric device, and means energized each time said target intercepts the light from said source for applying a compensating biasing voltage to said network at its transmitting end.

9. In a combination as disclosed, a facsimile picture transmitter including a support for a scene to be transmitted, a scanning head having a light source and photoelectric device, means for causing relative movement between said scanning head and support so as to successively scan elemental areas of a scene on said support, a transmission network connected to said photoelectric device, and means connected to said photoelectric device and energized intermittently thereby during relative movement between said support and scanning head for applying a compensating voltage to said network at its transmitting end.

10. In a combination as disclosed, a facsimile picture transmitter including a support for a scene to be transmitted, a scanning head having a light source and photoelectric device, means for causing relative movement between said scanning head and support so as to successively scan elemental areas of a scene on said support, a transmission network connected to said photo-

electric device, and means connected to said photoelectric device and energized intermittently thereby during relative movement between said support and scanning head for applying a compensating voltage to said network, said last means including an impedance network having a large time constant.

11. In a combination as disclosed, a facsimile picture transmitter including a support for a scene to be transmitted, a scanning head having a light source and photoelectric device, means for causing relative movement between said scanning head and support so as to successively scan elemental areas of a scene on said support, a transmission network connected to said photoelectric device, means connected to said photoelectric device and energized intermittently thereby during relative movement between said support and scanning head for applying a compensating voltage to said network, said last means including an impedance network having a large time constant, and means for applying a bucking voltage to said network to increase its sensitivity.

12. In a combination as disclosed, a facsimile picture transmitter including a support for a scene to be transmitted, a scanning head having a light source and photoelectric device, means for causing relative movement between said scanning head and support so as to successively scan elemental areas of a scene on said support, a transmission network connected to said photoelectric device, means connected to said photoelectric device and energized intermittently thereby during relative movement between said support and scanning head for applying a compensating voltage to said network, said last means including an impedance network having a large time constant, a second impedance network having an equal or a smaller time constant connected to said first network, and means for applying a bucking voltage to said second network.

13. In a system of the type described, a facsimile picture transmitter including a movable support for a scene to be transmitted, a scanning head operating in conjunction therewith to produce picture signals in accordance with the variations in the tonal value of the scene, a facsimile picture receiver including a support for a sensitized negative on which the original scene is to be recorded, a receiver including an amplifier for converting said signals into light variations and for applying them to the sensitized negative, a signal transmission network interconnecting the transmitter and the receiver, and means operated by the transmitter for applying a compensating signal to said network at the transmitting end at regular intervals.

14. In a facsimile picture transmitting and receiving system, the combination comprising a facsimile picture transmitter including a scanning head employing a photoelectric device, a facsimile picture recorder including a recording lamp, a transmission network interconnecting the transmitter with the recorder and including a signal amplifier at the transmitting end, means for periodically exciting said photoelectric device to produce a compensating signal, and means for intermittently applying said compensating signal to said amplifier to bias the amplifier so as to compensate for signal voltage drift of the photoelectric device.
